(57) **CLAIM**

The ornamental design for a container with integrated scale, as shown and described.

DESCRIPTION

FIG. 1 is a perspective view of a container with integrated scale, showing my new design;

FIG. 2 is a front side elevation view of the container with integrated scale of FIG. 1;

FIG. 3 is a rear side elevation view of the container with integrated scale of FIG. 1;

FIG. 4 is a left side elevation view of the container with integrated scale of FIG. 1;

FIG. 5 is a right side elevation view of the container with integrated scale;

FIG. 6 is a top plan view of the container with integrated scale of FIG. 1; and,

FIG. 7 is a bottom plan view of the container with integrated scale of FIG. 1.

The broken lines shown in the drawings do not form part of the claimed design.
